UNITED STATES PATENT OFFICE.

WILLIAM H. BUSH, OF FRAMINGHAM, MASSACHUSETTS.

FLYING-MACHINE.

1,213,585.

Specification of Letters Patent. Patented Jan. 23, 1917.

Application filed May 12, 1916. Serial No. 97,190.

To all whom it may concern:

Be it known that I, WILLIAM H. BUSH, a citizen of the United States, residing at Framingham, in the county of Middlesex and State of Massachusetts, have invented an Improvement in Flying-Machines, of which the following is a specification.

This invention relates to an improvement in aeroplanes, of the combination type 10 wherein permanently located buoyant bodies, as gas bags, or their equivalents, are utilized as a sustaining means, and planes provided for use in flight as in the ordinary heavier-than-air machine.

15 The buoyant bodies or gas bags, in the present machine, are arranged with a particular view to their utilization in maintaining the lateral stability of the machine in its direct elevation under the lifting propeller, and also with a view to maintaining the 20 longitudinal stability of the machine in the direct flight of the machine under the driving propeller.

25 Combination machines as heretofore constructed have proven difficult of flight in direct lines, owing to the air resistance of the gas bags, and the present invention aims to obviate this difficulty in constructing and arranging the gas bags to present the minimum air resistance while yet providing sufficient displacement to serve as sustaining 30 members. The gas bags are made up of independent sections grouped in particular relation to form a sustaining member of peculiar form, and are suitably sheathed to prevent rupture.

35 The propelling means involve independent elements such as lifting and driving propellers of any well-known type, and these 40 are selectively operated from a single motor or engine at the will of the driver, so that it is possible to utilize either the lifting or driving propeller under any and all conditions of service. The respective propellers 45 are particularly disposed with relation to the fixed gas bags in order that said gas bags may be utilized to provide, in a measure, banks of air against which the force of the propellers is more effectively directed.

50 The sustaining means, in the form of gas bags, are primarily designed for a displacement which will elevate a weight slightly less than that of the combined machine, driver, and contemplated passengers, and to 55 aid in sustaining the machine in flight there is provided wings or planes of any accepted

type, arranged on each side of and preferably below the gas bags. As these planes provide air resisting elements, the present invention contemplates their adjustment to 60 avoid such resistance when the machine is being directly elevated or lowered, to which end the planes are mounted upon the longitudinal axes and movable at the will of the driver, so that they may be arranged in 65 either of two angularly related positions, in one being presented at right angles to the longitudinal plane of the machine, to avoid air resistance in the direct elevation of the machine, and in the other to be arranged in 70 such longitudinal plane of the machine for use as sustaining members in flight. The adjustment of the planes adapt their use for air brakes in direct flight, and for air-resisting elements to prevent a too-rapid descent of the machine. 75

The driving propeller is designed to be utilized as a rudder, in that it may be deflected to one side or the other at the will of the driver, and also to be utilized as a flight 80 retarding element through provision of means for reversing the blades.

In the drawings, Figure 1 is a view in side elevation of the improved machine. Fig. 2 is a front elevation of the same. Fig. 3 is a broken sectional view of the sustaining gas bags. Fig. 4 is a vertical sectional view showing the separate bag structures. Fig. 5 is a broken transverse sectional view taken above the supporting planes, the gas bags 90 being omitted. Fig. 6 is a broken detail in elevation, showing the means for adjusting the planes and for locking them in adjusted relation. Fig. 7 is a front elevation of the same. Fig. 8 is a sectional detail showing 95 the mounting for the driving propeller to adapt it for use as a rudder. Fig. 9 is a side elevation of the same. Fig. 10 is a longitudinal sectional view of the same. Fig. 11 is a sectional detail partly in elevation, showing the locking means for the manually operable elements which control the rudder adjustment of the propeller. Fig. 12 is a detail in elevation showing the means for controlling the transmission intermediate the 100 driving shaft and respective propeller shafts. Fig. 13 is a broken view in elevation showing the brake mechanism for the forward landing wheels. Fig. 14 is a sectional view showing the lock for the manually operable 105 element of the braking mechanism, and, Fig. 15 is a view in elevation partly in section 110

illustrating the supporting and operative connections for the rear landing wheel.

In the preferred embodiment illustrated in the drawings, the improved machine comprises a main or body frame 1, preferably of skeleton form, and of sufficient size and so braced as to provide an adequate support for the operating parts, driver, and such passengers as the machine is designed to carry.

Rising from the body frame are the sustaining members 2, preferably gas bags. They are of identical construction, and each, as more particularly shown in Figs. 1 and 3, constitute skeleton frames 3, made up of a series of upright bars 4, connected by cross bars 5, and constituting side frames, brace bars 6 connecting the side frames and maintaining them in that spaced relation contemplated for the width of the particular gas bag. As a part of the frame thus provided, there is arranged a connecting bar 7 which extends throughout the outline of the particular gas bag and is shaped in accordance with such outline, the connecting bar 7 forming the edge bar of the gas bag and the respective ends of the cross bars 5 being curved inwardly in both directions into coincidence with the bar 7. Furthermore, in outline, the bar 7 is of peculiar shape, its lower ends being spaced apart a distance approximating the length of the body frame, the forward portion of the connecting bar extending upwardly and inclined forwardly from such body frame, the rear portion of the connecting bar also extending upwardly but having a greater degree of inclination from the body frame than the forward portion of such bar. The front and rear portions of the bar at their upper elements merge into curved or rounded form, constituting the upper outline of the gas bag. As thus arranged, it will be obvious that the maximum dimension of the gas bag, longitudinally of the machine, is near the extreme upper end of such bag, and that a materially greater portion of the gas bag is located in rear of the vertical plane of the body frame than is arranged forward of such plane. It is by reason of this structure, as will later appear, that the longitudinal stability of the machine is maintained during its forward flight.

The frame thus provided is supplied with a series of independent gas bags 8, preferably appropriately formed envelops extending throughout the height of the gas bag and disposed between the bars 6. The respective envelops 8 are wholly independent, one from another, which envelops may, if desired, be divided by transverse partitions to form a series of independent cells, though this familiar detail in a structure of this type is not deemed necessary of illustration. The gas bag proper, considered as an en-

tirety, is provided with a protecting covering 9, such as sheet metal or the like, overlying the frame described and following the outline thereof, as shown in Fig. 3. This covering acts to prevent puncture of the independent gas containers or envelops while at the same time preventing an undue distention of any one, providing, in effect, a rigid case within which are arranged the independent cells or envelops which are to be filled with buoyant gas.

An important feature of the present invention resides in the relative dispositions of the respective sustaining members, which will be generally hereinafter termed "gas bags," in that they are secured at their lower ends with their vertical axes in line with the extreme outer edges of the body frame and their horizontal axes longitudinally of such frame. Furthermore, the frames of the respective gas bags incline upwardly and outwardly from the body frame, or, in other words, diverge, presenting a maximum spacing at their extreme upper ends. Brace frames 10 connect the respective gas bag frames and maintain them in the fixed relation described, tie rods 11 being provided to further insure the security of the structure.

Rotatably supported, centrally of the brace frame, including the bars 10 is a propeller shaft 12, on the upper end of which is arranged a propeller 13 of any desired form, adapted for use as a lifting propeller. This propeller is arranged between the gas bags and below their extreme upper ends, operating thus at all times within the rectangular space of which the gas bags may be said to form side walls. The lower end of the propeller shaft terminates in a bevel gear 14 slightly above the body frame, and rotatably supported on an auxiliary frame structure 15 secured to the body frame and base frames is a second propeller shaft 16. This shaft supports the driving propeller 17 and is provided on its relatively forward end with a gear 18. The gears 14 and 18 are preferably arranged within a transmission case 19, into which also projects a driving shaft 20, from a motor 21, such as a gas engine or the like. The transmission mechanism includes a sleeve 22 keyed for longitudinal movement with the driving shaft 20, the sleeve having a bevel gear 23 and a spur gear 24 adapted to engage, when adjusted, the bevel gear 14 of the lifting propeller shaft and the spur gear 18 of the driving propeller shaft, respectively.

The transmission is controlled by a shifting lever 25 having pin-and-slot connection at 26, with the sleeve, the shaft of which lever is provided beyond the case 19 with angularly related arms 27, 28. The respective arms are connected by cables 29 and 30, which extend over suitable guide

pulleys 31, mounted on the frame, and are connected, respectively, to arms 32 and 33, supported upon the shaft 34, mounted upon the main frame within convenient reach of the foot of the driver. An operating lever 35 is connected to the shaft 34, and carries a spring-pressed catch 36, to engage one of a plurality of notches 37 in a notched segment 38 secured to the main frame. A spring 39 is connected to one of the arms as 33, and to an adjacent part of the main frame, the spring serving to induce action in one direction of the shaft 34, so that the operator may actuate the shaft in one direction, by pressure of his foot upon the terminal of the lever 35, and permit operation in the other direction under the influence of the spring 39.

Supporting planes 40 are designed to be used in connection with the sustaining members 2, these planes being specifically constructed in any desired manner and of any preferred material, as will adapt them for the use intended. The planes are mounted immediately below the lower ends of the sustaining members of gas bags, and, as it is obvious, that in case of flight, the planes will be disposed in the plane of flight, or slightly divergent therefrom, it is clear that in this position the planes would act to resist the direct elevation of the machine under the lifting propeller. To avoid this air resistance, the planes must be adjustable, and for this purpose they are mounted upon a transverse shaft 41, passing through the body frame, preferably at the upper portion thereof, the connections of the planes with the shaft being fixed. To permit adjustment, and to lock the planes in such adjusted position, the shaft 41 adjacent each side bar of the main frame, has secured thereon a disk 42 formed at preferred points with peripheral notches 43. Slidably supported in a bracket 44, secured to the main frame bar, is a latch 45 having a nose-end adapted for coöperation with either of the notches 43. The latch is spring-pressed in locking direction by a spring 46. The respective latches, there being one adjacent each longitudinal side bar of the main frame, are simultaneously operated through the medium of cables 47, terminally connected to the latches and extending vertically of the body frame and fixed at the lower ends to a preferred part thereof. As the driver's seat will be arranged at one side of the center of the main frame, one of the cables 47, that is from the relatively remote latch, may be guided through suitable pulleys 48 transversely of the main frame, so that it will depend immediately adjacent the cable from the remaining latch. Both cables may be thus grasped by one hand and drawn upon to operate the latches, such cables, if desired, being connected into one strand. The shaft 41 about centrally of the main frame is provided with a fixed cross bar 49, the ends of which are connected to the terminals of a cable 50 which extends downwardly and around a roller 51 ⁷⁹ mounted so that the cable is within convenient reach of the driver.

As illustrated in Fig. 6, I have shown locking means permitting of but two adjustments of the planes, though it will be understood that other adjustments may be readily provided for by the use of additional notches. By withdrawing the catches and suitably pulling upon one side or the other of the cable 50, the driver may adjust the planes, in the instance illustrated, to either a vertical or horizontal position, at will, providing for the use of such planes as sustaining planes during flight or their elimination as air resisting elements in the direct elevation of the machine.

The invention contemplates the use of a driving propeller as a rudder and also as a retarding or reverse driving element. In the use as a rudder, the propeller shaft 16 ⁸⁰ is provided with a universal joint 52 beyond the transmission case, and the end of the shaft adjacent the propeller is mounted in a carriage 53. The carriage is provided with a series of grooved rollers 54, adapted ⁹⁵ for travel on upper and lower track rails 55, arranged to present a curved path and suitably connected to the main frame, or to extensions thereof, if necessary. The propeller shaft 16 is thus free for lateral swing- ¹⁰⁰ movement, so as to position the propeller to one side or the other of the longitudinal axis of the machine, and hence utilize this propelling force for steering purposes. To control the degree of adjustment for this purpose, the respective sides of the carriage 53 are connected through cables 56, extended over suitably guiding pulleys, to hand bars 57 arranged on opposite sides of the driver seat, so that in the positive operation of either hand bar, the propeller shaft, and therefore the propeller, will be shifted laterally for use as a rudder.

To insure a neutral or normal driving position for the propeller, I contemplate locking the hand bars 57 when the parts are in such position. A simple means for this end is shown in Fig. 11, wherein each hand bar is provided with a fixed lug 58 adapted to be engaged by a spring-pressed lever 59 mounted in a suitable casing 60 through which the hand bar slides. A push button operator 61 is connected to one end of the lever to permit its manual operation to release the lock, when desired.

The driving propeller is also designed to be used as a retarder and reverse driver, gaining this result through a reversal of the propeller blades. This is accomplished at the will of the driver by means shown more ¹²⁵ ¹³⁰

particularly in Figs. 9 and 10, wherein the rear end of the propeller shaft is enlarged, or otherwise formed, to provide a hollow extension 62. The extension is formed with 5 diametrically opposed slots 63 through which extends the stub shaft 64 carrying the blades 65. On the shaft 64 within the hollow extension 62 is fixed a gear 66, and a rack 67 is secured within the extension to coöperate with the gear. The stub shaft 64 beyond the extension is rotatably mounted in brackets 68 extending forwardly from a ring 69 which slidably engages the extension 62. An annular operating member 70 10 circles the ring 69, having shouldered connections at 71 therewith, and being mounted for independent rotative movement there-through. The annular operating member 70 is connected, through the medium of links 72, with levers 73 secured upon a shaft rotatably mounted in the carriage 53, one lever 73 being below the shaft and connected on opposite sides of the fulcrum, through the medium of cables 74, 75, with the respective 15 ends of a bar 76 pivotally supported within reach of the driver, and controlled through a lever 77 having the usual notched segment locking means.

From the construction described, it is apparent that, through the operation of one 20 of the cables as 75, through the lever 77, the stub shaft 64 will be moved longitudinally, that is, toward or from the end of the extension 62, causing the propeller blades to 25 be reversed, owing to the rotation of the stub shaft through coöperation of the gear 66 and rack 67. Pull upon the other cable 74 will reversely actuate the stub shaft and again change the propeller blades. This 30 construction provides a means conveniently accessible to the driver, by which the driving propeller may be reversed, in effect, to utilize it as a retarding element in the flight of the machine, or as a reverse drive.

45 Landing mechanism or the means for supporting the machine on the surface of the ground involves a wheel structure, embodying, in the essential details, as illustrated, a pair of forward wheels 78 and a single 50 rear wheel 79, these wheels being movably mounted in bearings carried by auxiliary frames depending from the main frame. The forward wheels are mounted in bearing blocks 80 slidably in a bearing 81 in the 55 auxiliary frames, and cushioned against upward thrust by a spring 82. These wheels are preferably mounted upon a single shaft or axle 83, and the wheels are each provided with brake drums 84 to be engaged by the 60 usual brake bands 85. The brakes on both wheels are simultaneously operated through a shaft 86 connected for actuating said brakes, and centrally provided with a fixed radial arm 87, connected to the lower end 65 of the rod 88, which projects upwardly and

terminates in a head 89 within convenient reach of the foot of the driver. The brake rod 88 is spring pressed in the upward direction by spring 90, and may be locked in braking position through a cross bar 91 70 carried by the brake rod and engaging on the lower side of the plate 92 projecting from one of the main frame bars. The plate 92 is formed within an opening, which, at the upper end, is of a size to admit free 75 movement of the rod 88, and is laterally enlarged at the lower end, as at 93, to permit the passage of the bar 91 therethrough. In use, the brake rod is moved downwardly until the cross rod 91 is in line with the enlarged portion of the opening 93, whereupon pressure upon the brake rod causes the bar to pass through the opening, and, at the same time, so operate the shaft 86 as to set the brakes. Release of such pressure causes 85 the spring 90 to move the brake rod upwardly with the cross bar on the lower side of the plate 92, and thus maintain the brakes set. Obvious operation of the brake rod releases the brakes.

The rear wheel 79 is designed for use as a free supporting wheel, in order that it may readily follow the direction of travel of the machine on the surface. To permit such movement, the wheel is mounted in forks 94 90 having an upwardly extending post 95, which, as shown in Fig. 15, is mounted for free rotary movement in the sleeve member 96. The sleeve member is fixed against movement in the block 97 which is rotatably 100 mounted, preferably in the manner shown in said figure, upon one of the rear frame bars of the main or body frame. The upper end of the sleeve member 96 is connected by a spring 98 with the body frame, the 105 spring serving to maintain a normal position of the rear wheel, while permitting its vertical movement under strain, and on the main frame bar, the spring, of course, resisting such movement.

110 The improved machine provides sustaining members in the form of gas bags extended above the body frame and divergent, the gas envelop proper being sheathed to not only prevent puncture of said gas bags, 115 but to insure an absolutely uniform contour. The lifting propeller operates wholly between the gas bags and approximately at their point of maximum spread. As the gas bags are arranged below the propeller, 120 it is obvious that the air disturbed by such propeller will be banked, in effect, and thus render more effective the lifting action of such propeller. Furthermore, the gas bags present their minimum dimension in the line 125 of travel of the machine in the flying operation, and hence the air resistance incident to the presence of such gas bags is reduced to a minimum. Furthermore, it is to be noted, that assuming the center of the body 130

frame as the longitudinal axis of the machine, a larger proportion of the gas bags is in rear of such axial line. This increases the buoyant tendency in the rear of the machine, and hence the driving action of the driving propeller with its tendency to disturb the longitudinal stability of the machine is overcome, and the machine completed to travel in an upright position. The divergence of the gas bags is also important, as it tends to counteract any tendency to a lateral tilting of the machine in rising. The supporting planes are to be turned to a vertical position during the direct upward movement of the machine under the influence of the lifting propeller, and are then to be turned to a horizontal position for supporting purposes during the travel of the machine, under the influence of the driving propeller. However, if, during the driving action, it is desirable to retard the machine, it is possible to secure such effect by reversing the blades of the driving propeller, or, if increased retardation is desired, by again turning the planes to the vertical position, so that they will act as brakes. The driving propeller through the means hereinbefore described, may be shifted laterally so that it will readily serve as a rudder in controlling the movement of flight.

The machine shown provides a seat support 99 on which is arranged a driver's seat 100 and a passenger seat 101. Various controls hereinbefore described are, of course, to be within convenient reach of the driver, and, if desired, in order to avoid disturbing the stability of the machine, a weight of preferred form (not shown) may be carried in the passenger seat, in the absence of a passenger.

The motor is here illustrated as a gas engine, and a sprocket and chain connection 102 extends from the crank shaft of such motor to a hand crank shaft 103 for cranking purposes. Fuel supply from a tank 104 is supported between the gas bags above the motor and a carburetor 105 receiving the supply by gravity through a feed pipe 106.

Through a series of cables and levers, designated generally by 107, I extend a means within reach of the driver for the control of the gas supply to the engine.

All of the details of the motor, fuel connections, and control are designed to be merely typical illustration, as any preferred details in this connection may be used.

I claim:

1. A flying-machine comprising a body frame, gas bags extended above said frame in upwardly divergent relation, means arranged between the gas bags for elevating the machine and means arranged beyond the gas bags for propelling the machine.

2. A flying-machine comprising a body

frame, gas bags having their maximum dimension vertically of the machine including a shell of fixed maximum contour rising above the body frame, means for elevating the machine, and means for propelling the machine, the gas bags extending forwardly and rearwardly of the body frame with the rearward extension of greater area to maintain longitudinal stability of the machine under the action of the driving means.

3. A flying-machine comprising a body frame, gas bags rising from the respective sides of the frame in upwardly divergent relation, each gas bag including a metallic sheathing of fixed contour, a series of independent gas envelops arranged in the sheathing and a frame supporting the sheathing and dividing the gas envelops, elevating means for the machine arranged between the gas bags and a propelling means for the machine arranged in rear of the gas bags.

4. A flying-machine comprising a body frame, gas bags rising therefrom in upwardly divergent relation, and elevating means for the machine arranged between the gas bags, and propelling means for the machine arranged in rear of the gas bags, and supporting planes secured to and projecting beyond the body frame.

5. A flying-machine comprising a body frame, gas bags rising therefrom in upwardly divergent relation, and elevating means for the machine arranged between the gas bags, and propelling means for the machine arranged in rear of the gas bags, and supporting planes secured to and projecting beyond the body frame, and means carried by the body frame for adjusting the supporting planes into a plurality of angularly related positions to permit said planes to be turned in approximate line of movement of the machine in elevating and in driving.

6. A flying-machine comprising a body frame, a plurality of spaced gas bags therefor, supporting planes arranged approximately at the juncture of the gas bags and the body frame, means for similarly adjusting said planes into either of two right-angularly related positions, means arranged between the gas bags for elevating the machine and means arranged in rear of the gas bags for driving the machine.

7. A flying-machine comprising a body frame, gas bags secured at their lower edges to the upper side edges of the frame, said gas bags being upwardly divergent with respect to the frame, an elevating propeller for the machine arranged below the upper ends of the gas bags and in the space between them to utilize the converging space between the gas bags below said propeller to bank the air and a driving means for the machine arranged in rear of the gas bags.

8. A flying-machine comprising a body frame, gas bags rising therefrom in up-

- wardly divergent relation, an elevating propeller for the machine arranged intermediate the gas bags, the divergent relation of said gas bags serving to maintain the lateral stability of the machine in rising, said gas bags 5 extending forwardly and rearwardly of the plane of the body frame with the maximum extension in rear thereof, and a driving means for the machine arranged in rear of the gas bags and below the extended portion thereof, the increased rearward extension of the gas bags serving to maintain the longitudinal stability of the machine in forward flight.
- 10 9. A flying-machine comprising a body frame, gas bags rising therefrom, elevating and driving propellers for said machine, a shaft mounted transversely of the body frame, supporting-planes secured to said shaft on opposite sides of the frame, notched disks secured upon said shaft, spring-pressed latches carried by the frame to engage the notches in the disk, means extended to the body frame for operating the latches to release the disks, a cross-bar secured to the shaft and an operating cable connected to the respective ends of the cross-bar, and movably connected to a guide element on the body frame and serving to turn the shaft 20 to angularly adjust the supporting-planes following operation of the latches to release the locking disks.
- 15 10. A flying-machine comprising a body frame, gas bags and supporting planes carried thereby, said gas-bags having their maximum dimensions vertically of the body-frame, an elevating propeller arranged intermediate the gas bags, a driving propeller arranged in rear of the gas bags, a motor 25 carried by the body frame, a transmission for selectively operating the elevating propeller or driving propeller, and means for operating the transmission.
- 20 11. A flying-machine comprising a body frame, divergent upwardly extending gas bags and adjustable supporting planes carried thereby, an elevating propeller arranged intermediate the gas bags, an operating shaft therefor, a driving propeller arranged in rear of the gas bags, an operating-shaft therefor, a motor having a driving-shaft, a transmission including a sleeve mounted on the driving-shaft having gearing connections for the respective propeller shafts, and 30 means for operating said sleeve to selectively gear the driving-shaft to either propeller shaft.
- 25 12. A flying-machine comprising a body frame, upwardly extending and divergent gas bags and adjustable supporting planes carried thereby, an elevating propeller arranged intermediate the gas bags, a driving propeller arranged in rear of the gas bags, and including an operating-shaft having a 35 universal connection and means for swing-
- ing the propeller connected end of said shaft on the universal connection to one side or the other of the normal driving position to utilize said driving propeller as a rudder.
- 30 13. A flying-machine comprising a body frame, upwardly extending and divergent gas bags and adjustable supporting planes carried thereby, an elevating propeller arranged intermediate the gas bags, a driving propeller arranged in rear of the gas bags, and having a driving-shaft with a universal connection, a carriage for rotatably supporting the propeller connected end of said shaft, a track secured to the body frame on which the carriage is adapted for movement, and means for moving the carriage in either direction on said track to shift the propeller to one side or the other of the normal driving position for use as a rudder.
- 35 14. A flying-machine comprising a body frame, gas bags and supporting planes carried thereby, an elevating propeller arranged intermediate the gas bags, a driving propeller arranged in rear of the gas bags, and having a driving-shaft formed with a hollow terminal, a stub-shaft to which the propeller blades are connected mounted for longitudinal movement in said hollow terminal, a gear carried by the stub-shaft within the hollow terminal, a rack secured within the hollow terminal to be engaged by the gear, and means for shifting the stub-shaft longitudinally of the hollow terminal to reverse the propeller blades.
- 40 15. A flying-machine comprising a body frame, having gas bags and supporting planes, an elevating propeller arranged between the gas bags, a driving propeller arranged in rear of the gas bags, and having a driving-shaft including a universal joint, a carriage rotatably supporting the shaft and movable on the track carried by the body frame to shift the propeller for use as a rudder, means for operating the carriage, the propeller end of the driving-shaft forming a hollow terminal, a stub-shaft carrying the propeller blades mounted for movement longitudinally of said hollow terminal, gearing connections within said hollow terminal to turn the stub shaft in such longitudinal movement, and means adapted for manual operation to move the stub shaft longitudinally of the hollow terminal of the driving-shaft.
- 45 16. A flying-machine comprising a body frame, gas bags and supporting-planes carried thereby, an elevating-propeller arranged between the gas bags, a driving-propeller arranged in rear of the gas bags and including an operating-shaft having a universal joint, means for mounting the propeller connected end of the shaft for bodily movement to one side or the other of the normal driving position to utilize the propeller as a rudder, operating-members for such

means extended to and having control elements mounted on the body frame, connections between the propeller blades and operating shaft to reverse the position of said blades at will, means for operating the connections including cables extended to the body frame and connected to control elements thereon.

17. A flying-machine comprising a body frame, gas bags and supporting-planes carried thereby, driving and elevating propellers connected to the frame, and a landing and ground-traveling structure including forward wheels and a rear wheel, a block for supporting the rear wheel mounted for rotation on a fixed part of the body frame, a sleeve longitudinally movable in said block, a wheel-carrying frame mounted for free rotative movement in said sleeve, and a spring connecting one end of the sleeve with the body frame to normally position the block with respect to the frame.

18. A flying machine comprising a body-frame, gas-bags extending above said frame in upwardly divergent relation, and elevating means arranged between the gas bags.

19. A flying machine comprising a body-frame, having upwardly extending divergent gas bags, and propelling means arranged between and adjacent the upper ends of the gas bags.

20. In a flying machine, a body frame, a lifting propeller arranged above the body

frame, casings rising from the body frame on opposite sides of and extending above the propeller, and a series of independent gas containers arranged in each casing.

21. In a flying machine, a body frame, a lifting propeller arranged above the body frame, and casings for gas containers rising from the body frame on opposite sides of and extending above the propeller, each casing being of gradually increased cross section from the body frame toward the propeller.

22. In a flying machine, a body frame, a lifting propeller arranged above the body frame, and casings for gas containers rising from the body frame on opposite sides of and extending above the propeller, said casings having their maximum cross section just below the propeller.

23. In a flying machine, a body frame, a lifting propeller arranged above the body frame, and casings for gas containers rising from the body frame on opposite sides of and extending above the propeller, said casings extending beyond the propeller, forwardly and rearwardly thereof.

In testimony whereof, I have signed my name to this specification, in the presence of two subscribing witnesses.

WILLIAM H. BUSH.
